(57) **CLAIM**

The ornamental design for an outdoor dog kennel cover, as shown and described.

DESCRIPTION

FIG. 1 is a front, right and top perspective view of an outdoor dog kennel cover, showing my new design.

FIG. 2 is a rear, left and bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is an enlarged view of portion 9 shown in FIG. 1; and,

FIG. 10 is an enlarged view of portion 10 shown in FIG. 2.

The dot-dash broken lines depict the boundaries of the enlargements that form no part of the claimed design. The broken lines in the figures illustrate portions of the outdoor dog kennel cover that form no part of the claimed design.
